UNITED STATES PATENT OFFICE.

RICHARD WELLS COUNCER, OF EGREMONT, ENGLAND.

DESIGN FOR A HOLDER FOR FOUNTAIN-PENS.

SPECIFICATION forming part of Design No. 34,775, dated July 16, 1901.

Application filed May 6, 1901. Serial No. 59,060. Term of patent 7 years.

To all whom it may concern:

Be it known that I, RICHARD WELLS COUNCER, a subject of the King of Great Britain, residing at Egremont, England, have invented 5 and produced a new, useful, and original Design for a Holder for Fountain-Pens, of which the following is a specification, reference being had to the accompanying drawing, which is a perspective view of a holder embodying my design.

The holder is formed of a wire bent upon itself at *a*, forming a straight portion *b*, a curved part *c*, a straight portion *g*, oblique to the portion *b*, a curved portion *d*, a straight portion *h*, substantially parallel to the portion *b*, and two semicircular portions *e e*, substantially at right angles to the portion *h* and forming a circle with the ends of said portions *e e* adjacent at *f*.

The leading features of my design are the 20 straight portions *b*, *g*, and *h*, connected by the curved portions *c* and *d*, and the two semicircular portions *e e*, forming a circle and substantially at right angles to the portions *b* and *h*. 25

I claim—

The design for a holder for fountain-pens, substantially as shown and described.

In witness whereof I have hereunto signed my name, this 24th day of April, 1901, in the 30 presence of two subscribing witnesses.

RICHARD WELLS COUNCER.
